(57) **CLAIM**

The ornamental design of mounting device, substantially as shown and described.

DESCRIPTION

FIG. 1 is a top right perspective view of a mounting device showing my new design, a top left perspective view thereof being the same as the top right perspective view shown in FIG. 1; and,

FIG. 2 is a bottom left perspective view thereof, a bottom right perspective view thereof being the same as the bottom left perspective view shown in FIG. 2.

1 Claim, 2 Drawing Sheets
